Primary Examiner — Karen E Eldridge Powers

(57) **CLAIM**

The ornamental design for a lint brush vacuum attachment, as shown and described.

DESCRIPTION

FIG. 1 is a front elevational view of a lint brush vacuum attachment showing my new design;

FIG. 2 is a rear elevational view of the lint brush vacuum attachment;

FIG. 3 is a right side elevational view of the lint brush vacuum attachment;

FIG. 4 is a left side elevational view of the lint brush vacuum attachment;

FIG. 5 is a top plan view of the lint brush vacuum attachment;

FIG. 6 is a bottom plan view of the lint brush vacuum attachment; view thereof; and,

FIG. 7 is a top, front and side perspective view of the lint brush vacuum attachment.
